UNITED STATES PATENT OFFICE

JOHN Q. WALTON, OF WASHINGTON, DISTRICT OF COLUMBIA, ASSIGNOR TO WESTINGHOUSE ELECTRIC AND MANUFACTURING COMPANY, A CORPORATION OF PENNSYLVANIA

MARINE PUMPING SYSTEM

Application filed March 28, 1930. Serial No. 439,798.

My invention relates to marine pumping systems and particularly to pumping systems for rapidly removing the water from a ship's bilge or from compartments of a ship which have become flooded and it has for an object to provide a system of the character designated which shall be capable of removing water from the ship at a highly rapid rate and which shall have adequate 10 capacity for removing large quantities of water which may enter the ship in times of serious accident.

Heretofore, it has been customary to provide all ships with a bilge pumping system 15 for periodically removing relatively small quantities of water which normally accumulate in the various compartments. However, pumping systems of this character, as ordinarily provided, do not have sufficient 20 capacity for maintaining the buoyancy of the ship at such times as a serious accident has occurred and the inrush of water into the ship has attained extraordinary proportions. If the pumping system of the prior 25 art were so enlarged as to give it the required capacity to cope with the emergency situations of this nature, the weight and the space occupied by such a system would attain such large proportions as to make the 30 idea impractical.

It has, therefore, been proposed to provide a bilge or salvage pumping system which embodies a pump or pumps of the propeller type, a pump of this type having already 35 been developed which, although relatively small in size and relatively low in weight, is capable of translating tremendous quantities of water at high velocity. It therefore becomes practical, by utilizing pumps 40 of this character, to provide a bilge pumping system for a ship having a large enough pumping capacity to maintain the buoyancy of the ship in times of serious accident.

It is, therefore, a particular object of my 45 invention to provide a bilge or salvage pumping system which shall embody a pump of the propeller type so arranged, in relation to the ship's hull structure, as to occupy 50 a minimum amount of space, entail a mini-

mum amount of weight and require very little or no connecting piping.

It has for a further object to provide a bilge or salvage pumping system of the foregoing character which shall be so arranged 55 that it may be readily applied to existing ships without involving serious alterations in the ship's structure and without requiring the extension of any piping to the upper side of those portions of the ship which contain 60 the living quarters.

These and other objects are effected by my invention, as will be apparent from the following description and claims taken in connection with the accompanying drawings, forming a part of this application, in 65 which:

Fig. 1 is a view, in transverse section, of a ship provided with one form of pumping system arranged in accordance with my 70 invention;

Fig. 2 is a detail view, in sectional elevation, of the pump and sea chest embodied in the pumping system shown in Fig. 1; and,

Fig. 3 is a view, in elevation, of another 75 embodiment of my invention, wherein the pump slidably extends through the ship's inner bottom.

In accordance with my invention, I propose to telescope the pumping apparatus 80 within the inner bottom or tank top of the ship with the inlet of the pump located adjacent to the upper surface of the tank top and the discharge of the pump extending toward and being directly connected to 85 the skin of the ship. In this way, a considerable portion of the pump is housed between the inner bottom and the skin of the ship while, at the same time, very little or, in some cases, no suction piping is required 90 for the pump. With such an arrangement, the ship's structure readily lends itself to provide an adequate supporting structure 95 for the pump.

Referring now to Fig. 1 of the drawings, I show a ship's hull indicated generally at 10 and including a shell or skin 11 and an inner bottom or tank top 12. An upper or main deck is represented at 14.

Secured to and communicating with the 100

exterior of the skin 11 of the ship is a discharge sea chest 15 upon which is mounted a sea valve 16. Telescopically arranged within the inner bottom or tank top 12 is 5 a propeller pump 17 which is mounted upon the sea valve 16. An opening 18 is provided in the inner bottom through which the pump 17 may be inserted, the latter being 10 preferably arranged telescopically with respect to the tank top or inner bottom.

As shown particularly in Fig. 2, the propeller pump 17 embodies a housing or body portion 19 having a laterally-extending, annular inlet portion 20, and axially-extending, 15 throat portion 21 and an axially-extending, diverging portion 22 terminating in an outlet 23. The lower wall 20' of the annular intake portion 20 is preferably secured by some means, such as rivets 24, to the inner 20 bottom or tank top in order that the pump may effect a water-tight joint, 25, with the tank top and thus maintain the water-tight integrity of the latter.

Disposed in the throat portion 21 of the 25 pump body is a screw propeller 26 retained upon a tapered portion 27 of a pump shaft 28 by means of a nut 29. Disposed below and adjacent to the propeller 26 are a plurality of circumferentially-spaced, stationary 30 guide vanes 31, which guide vanes converge toward a central conical or fairing member 32 having an outer diameter approximately equal to the diameter of the propeller hub in order to provide a smooth annular 35 passageway for the water circulating through the pump. Disposed within the conical member 32 is a bearing 33 which cooperates with a reduced diametral projecting journal portion 34 of the pump shaft 28 to maintain 40 the latter in axial alignment.

Disposed above and supported upon the inlet annulus 20 of the pump is a motor such as, for example, a steam turbine 35 for driving the propeller 26. As shown, the turbine 45 embodies a casing 36 in which is housed a turbine rotor wheel 37 secured to the pump shaft 28 by means of a nut 38. Suitable turbine blades 39 are spaced about the periphery of the turbine wheel 37 in a manner 50 well understood in the art. The casing 36 is provided with a steam inlet 41 and an exhaust outlet 42, the steam inlet 41 communicating, in the turbine casing 36, with a suitable nozzle chamber 42' for directing 55 the steam against the turbine blades. For preventing leakage of steam between the turbine casing 36 and the pump shaft 28, a suitable sealing gland 43 is provided. Suspended from the turbine casing 36 is a thrust 60 bearing housing 44 supporting a thrust bearing 45. The latter cooperates with a collar 46 on the pump shaft 28 for supporting the pump shaft as well as the propeller 26 and the turbine rotor wheel 37 in proper axial 65 position.

The sea valve 16, being located below the inner bottom or tank top of the ship, is preferably provided with an operating gear for facilitating opening and closing movements of the same. As shown in Fig. 1, this operating gear may, for example, comprise 70 a pair of bevel gears 47, one of the gears being provided on the stem of the valve and the other gear upon an operating rod 48 projecting upwardly through the inner bottom 12. With an operating gear of this character, a gate valve of the type which has a non-rising stem is preferably employed. Where the operating rod 48 projects through the inner bottom 12, a suitable stuffing box 49 is provided in order to afford a fluid-tight joint. 75

Provided on the steam inlet 41 of the turbine is a throttle valve 51. While the throttle valve 51 and the sea valve 16 may be operated independently of each other, I prefer to operate them concurrently from a common operating gear. Accordingly, I provide, on the operating rod 48, a pinion 52 meshing with a gear 53 provided on the 80 stem of the throttle valve. As the stem of the sea valve 15 may require many more turns to effect full opening or closing movements than the stem of the throttle valve 51, the gears 52 and 53 are preferably so 85 proportioned that the gear 52 on the operating shaft 48 effects several turns to one turn of the gear 53 on the throttle valve stem. With such an arrangement, both valves may be concurrently opened or closed 90 by proper manipulation of the operating rod 48. 100

When it is desired to utilize the pump 17 for removing limited quantities of water from the bilge in more or less of a routine manner, the rod 48 may be operated by means of a hand wheel 54 which is readily accessible from the floor plating. However, in times of serious emergency, it may be desirable to manipulate the rod 48 from some 105 upper deck and, hence, I preferably extend the operating rod 48 upwardly through the main or weather deck 14 and provide it with a supplementary hand wheel 55. 110

Should, by any chance, some obstruction 115 prevent closure of the sea valve 16, there is associated with the inlet 20 of the pump 17 a valve 56, which valve may be utilized to seal off the inlet of the pump and prevent flooding of the ship when the pump has been 120 stopped. As shown in Fig. 2, the inlet annulus 20 of the pump is provided with upper and lower seats 57 and 58 while the valve 56 is made annular and is provided with circular valve faces 59 and 60 which cooperate, 125 respectively, with the seats 57 and 58 to effect a seal. As shown in full lines in Fig. 2, the inlet annulus 20 of the pump is unsealed by lifting the valve 56, a plurality of circumferentially-spaced, radially-extending 130

ribs 61 being provided in the valve, which ribs have bearing surfaces 62 engaging the inlet of the pump for guiding the opening and closing movements of the valve. Preferably, the valve is raised approximately one half the height of the inlet annulus 20 and the water is free to enter the latter by flowing in the directions indicated by the arrows. When closed, the valve assumes the 10 position indicated in dot and dash lines.

Preferably, the valve 56 is raised and lowered by a separate operating gear 63 embodying an operating rod 64 having a hand wheel 65 operable from a position adjacent 15 to the pump and a hand wheel 66 operable from an upper deck. The rod 64 engages, by means of a screw thread 67, the hub portion 68 of a yoke 69 secured to the valve 56. The rod 64 may be supported at its lower 20 end in a bearing 71 carried by the casing of the turbine 35. Rotational movement of the yoke 69 and the valve 56 may be prevented by a stationary guide pin 72 projecting through a hole in the yoke.

25 As shown in Fig. 1, the pump 17 is preferably located in a separate water-tight compartment or coffer dam 73 formed between the inner plating structure 12 and the shell 11 by partitions 74 and 75 which extend longitudinally between two frames of the ship.

From the foregoing description, the operation of my improved pumping system will be apparent. Assuming, first of all, that the ship has been involved in some 35 serious accident that its hull structure has been so punctured as to permit tremendous quantities of sea water to pour into the ship; immediately, the buoyancy of the ship is endangered. At a time like this, either the 40 hand wheel 54 or the hand wheel 55 is manipulated to effect simultaneous opening of the throttle valve 51 and the sea valve 16. In case the valve 56 is not already disposed in an open position, the operating gear 63 is 45 also manipulated to raise the valve 56. As a result, the turbine 35 is energized and the propeller 26 is rotated. The water flooding into the ship enters the annular intake 20 of the pump 17 and is discharged by the 50 propeller through the outlet 23 to the sea chest 15 and thence to the sea. As stated heretofore, pumps of the propeller type are capable of handling very large quantities of water at high velocities and, hence, with 55 the form of arrangement proposed, it is perfectly feasible to install a pump of such large capacity that even though the ship be seriously damaged and the inrush of water reach extensive proportions, the pump 60 has adequate capacity for removing the water as fast as it enters. The buoyancy of the ship is therefore maintained and foundering is prevented.

65 As will be apparent from the drawings, the pump is preferably so located that its

annular intake 20 is disposed adjacent to the inner bottom so that no suction piping is required. Furthermore, a considerable portion of the pump is housed between the inner bottom and the skin of the ship so that only 70 a small portion of the pump projects above the floor plating. The discharge portion of the pump projects directly toward the skin of the ship and, hence, the only connections intervening between it and the skin of the ship may be the sea chest and the sea valve. 75

After the water is removed from the ship, the sea valve 16 is closed and the pump 17 is then stopped. If, by any chance, some 80 obstruction may prevent closure of the sea valve 16, the valve 56 is lowered to a closed position before stopping the pump.

In Fig. 1, I show an arrangement wherein the pump is supported in part upon the inner bottom or the tank top and in part 85 upon the skin of the ship and wherein the pump and its connecting valve or sea chest are rigidly secured in a fluid-tight manner to both the inner bottom or tank top and the skin of the ship. However, I may, as 90 shown in Fig. 3, so arrange the pump that the inner bottom is displaceable relative to the pump. This may be accomplished by providing a suitable opening 61 in the inner bottom or tank top through which the pump 95 body projects. Secured to the inner bottom or tank top about the opening 61 is a reinforcing ring 62 upon which a gland body 63 is secured. Suitable packing 64 as well as a suitable gland 65 are associated with the 100 gland body in a manner well understood in the art. Both the gland body 63, as well as the gland 65 are split diametrically in order to facilitate assembly and disassembly. By means of the foregoing arrangement the 105 pump may be axially displaced relative to the inner bottom or tank top without affecting the water-tight qualities of the inner bottom or tank top.

In the foregoing embodiments, I have 110 shown a single pump associated with a single ship's compartment. However, it will be obvious that, in providing a complete bilge or salvage pumping system for a large ship including a substantial number of water-tight sub-divisions or compartments, a pumping system of the character shown in the drawings may be provided for each or for several of the compartments. By providing a multiple pumping system of this 115 character, it will be possible to maintain very large ships afloat for indefinite periods of time even though they be seriously damaged and there be a constant inrush of sea water into one or more of their compartments. 120

125 While I have shown my invention in two forms, it will be obvious to those skilled in the art that it is not so limited, but is susceptible of various other changes and modifications without departing from the 130

spirit thereof, and I desire, therefore, that only such limitations shall be placed thereupon as are imposed by the prior art or as are specifically set forth in the appended claims.

5. What I claim is:—

1. The combination with a ship's structure embodying a shell and an inner plating structure spaced from the shell, of a propeller pump disposed, at least in part, between the inner plating structure and the shell, said pump having its axis of revolution extending transversely of the inner plating structure and the shell and having an inlet connecting with the inner side of the inner plating structure and an outlet extending axially of the pump and disposed adjacent to the shell, and means including a sea chest and a sea valve for connecting the outlet of the pump to the shell and for supporting the pump from the shell.

2. The combination with a ship's structure embodying a shell and an inner plating structure spaced from the shell, of a pump extending through the inner plating structure and having its inlet portion disposed interiorly of the inner plating structure and its outlet portion disposed between the inner plating structure and the shell, and means for connecting the pump outlet portion with the exterior of the shell.

3. The combination with a ship's structure embodying a shell and an inner plating structure spaced from the shell, of a pump having its inlet portion located interiorly of and adjacent to the inner plating structure and its outlet portion projecting through the inner plating in the direction of the shell, and means for connecting the outlet portion of the pump to the exterior of the shell.

4. The combination with a ship's structure embodying a shell and an inner plating structure spaced from the shell, of a pump supported upon and depending from the inner plating structure of the ship, said pump having its inlet communicating with the space above the plating structure, and means for connecting the outlet of the pump to the shell of the ship.

5. The combination with a ship's structure embodying a shell and an inner plating structure spaced from the shell, of a pump extending through the inner plating structure of the ship, said pump embodying an inlet located on the inner side of the inner plating structure and an outlet located on the outer side of the inner plating structure, and means for connecting the outlet to the exterior of the shell of the ship and providing for supporting the pump from the shell of the ship.

6. The combination with a ship's structure embodying a shell and an inner plating structure spaced from the shell, of a pump

extending through the inner plating structure of the ship, said pump embodying an inlet located on the inner side of the inner plating structure and an outlet located on the outer side of the inner plating structure, means for connecting the outlet to the exterior of the shell of the ship and providing for supporting the pump from the shell of the ship, and means for effecting a fluid-tight joint between the inner plating structure and the pump.

7. The combination with a ship's structure embodying a shell having a discharge opening provided therein and also embodying an inner plating structure spaced from the shell, of a pump body extending through the inner plating structure and having an inlet annulus located inwardly of the inner plating structure and an outlet located adjacent to the shell of the ship, means including a sea valve for connecting the outlet to the discharge opening in the shell of the ship, a propeller disposed in the pump body and arranged to receive water from the annulus and to discharge the same to the outlet, and a motor for driving the propeller mounted upon the annulus.

8. The combination with a ship's structure embodying a shell having a discharge opening provided therein and also embodying an inner plating structure spaced from the shell, of a pump body extending through the inner plating structure and having an inlet located inwardly of the inner plating structure and an outlet located between the inner plating structure and the shell and extending toward the shell of the ship, means including a sea valve for connecting the outlet to the discharge opening in the shell of the ship, a propeller disposed in the pump body intermediate of its inlet and its outlet, stationary guide vanes disposed on the discharge side of the propeller and within the pump body for removing the twist or swirl of the water discharged by the propeller, and a motor for driving the propeller located interiorly of the inner plating structure.

9. The combination with a ship's structure embodying a shell and an inner plating structure spaced from the shell, of a pump having a laterally-extending inlet connecting with the inner side of the inner plating structure, an axially-extending outlet disposed between the inner plating structure and the shell and a propeller disposed between the inlet and the outlet for translating fluid therebetween, a sea chest provided on the shell of the ship and connecting with the outlet of the pump and a motor for driving the pump located inwardly of the inner plating structure, said motor, propeller, and sea chest being disposed in axial alignment.

10. The combination with a ship's struc-

ture embodying a shell and an inner plating structure spaced from the shell, of a sea chest mounted upon the inner side of the shell of the ship, a sea valve mounted upon 5 the sea chest, a propeller pump mounted upon the sea valve, said propeller pump having an axially-extending outlet connecting with the sea valve and a laterally-extending inlet disposed on the inner side of the inner plating 10 structure, and a motor mounted upon the pump for driving the same.

11. The combination with a ship's structure embodying a shell and an inner plating structure spaced from the shell, of a propeller pump extending through the inner plating structure and having an inlet communicating with the inner side of the inner plating structure and an outlet located between the inner plating structure and the 15 shell, means including a sea valve for connecting the outlet of the pump to the exterior of the shell of the ship, said sea valve being located between the inner plating structure and the shell of the ship, and 20 means for operating said sea valve from the inner side of the inner plating structure.

12. The combination with a ship's structure embodying a shell and an inner plating structure spaced from the shell, of a propeller pump extending through the inner plating structure and having an inlet communicating with the inner side of the inner plating structure and an outlet located between the inner plating structure and the shell, 25 means including a sea valve for connecting the outlet of the pump to the exterior of the shell of the ship, said sea valve being located between the inner plating structure and the shell of the ship, a motor located on the 30 inner side of the inner plating structure for driving the pump, means for controlling the supply of motive energy to the motor, and a common control system for operating both the sea valve and the motive energy 35 controlling means, said control system being operative on the inner side of the inner plating structure.

13. The combination with a ship's structure embodying an upper deck, a shell and 50 an inner plating structure spaced from the shell, of a pump extending through the inner plating structure for removing water from the inner side of the inner plating structure, said pump having its outlet located between the inner plating structure and the shell, means including a sea valve for connecting the outlet of the pump with the exterior of the shell of the ship, said sea valve being located between the inner plating structure and the shell, a motor for driving the pump located on the inner side of the inner plating structure, means for admitting motive energy to the motor, a common control system for both the sea valve 55 and the motive energy admission means,

and means for operating said control system both from below and above the upper deck of the ship.

14. The combination with a ship's structure embodying a shell and an inner plating structure spaced from the shell, of a bilge or salvage pump disposed, at least in part, between the inner plating structure and the shell, said pump having an inlet and an outlet and having its inlet communicating with the inner side of the inner plating structure, means for connecting the pump outlet with the exterior of the shell, and means forming a separate, water-tight compartment for the pump between the inner 70 plating structure and the shell.

In testimony whereof, I have hereunto subscribed my name this 28th day of March, 1930.
